UNITED STATES PATENT OFFICE.

WILLIAM JANSON ROCHE, OF NEW BETHLEHEM, PENNSYLVANIA,
ASSIGNOR OF ONE-HALF TO EDWARD F. BITTNER, OF NEW
BETHLEHEM, PENNSYLVANIA.

GAME.

No. 836,537.

Specification of Letters Patent.

Patented Nov. 20, 1906.

Application filed August 14, 1906. Serial No. 330,541.

To all whom it may concern:

Be it known that I, WILLIAM JANSON ROCHE, a citizen of the United States of America, residing at New Bethlehem, in the county of Clarion and State of Pennsylvania, have invented certain new and useful Improvements in Games, of which the following is a specification, reference being had therein to the accompanying drawings.

10 This invention relates to games, and more particularly to a card game in which several series of cards bearing different designations are employed to simulate and fix the record or score of an automobile race.

15 The invention consists of a number of series of cards, each card bearing certain designations peculiar to its series and all of the cards being designed to be included in a single pack adapted to be shuffled and dealt to players 20 and to provide a novel and interesting game.

The improvement will be specifically described hereinafter in connection with the accompanying drawings, which form a part of this specification, and its novel features will 25 be defined in the appended claims.

In the drawings, Figure 1 is a front elevation of four cards constituting one series. Fig. 2 is a similar view of three cards constituting a second series. Fig. 3 is a similar 30 view of three cards forming a third series, and Fig. 4 is an elevation of two cards constituting a fourth series.

The first series (shown in Fig. 1) comprises a plurality of cards, four being shown, designated by the reference-numerals 1, 2, 3, and 4, respectively. The card 1 bears the designation "1 mile" printed thereon across its ends in reverse lines, so that the number "1" and the word "mile" may be read from either 40 end of the card. I preferably also ornament the card with two illustrations of an automobile, said illustrations being reversely arranged, as shown, to correspond to the printed lines above them.

45 The cards 2, 3, and 4 are similar to the card 1, except that said cards respectively bear the designations "3 miles," "5 miles," and "10 miles."

In the second group or series of cards (shown 50 in Fig. 2) the card 5 bears the words "Delay 1 hour—Collision" duplicated in reverse order at the end of the card.

The card 6 has printed thereon in duplicate

reversed order "Delay 1 hour—Out of gasoline" and the card 7 bears the words "Delay 55 2 hours—Puncture" in duplicate and reversed as above described.

Of the series of cards shown in Fig. 3 the card 8 bears the words "Hauled in" at each end thereof. The card 9 bears the words 60 "Go—The start" at each end, and card 10 the word "Gasolene."

The card 11 of the series shown in Fig. 4 has printed thereon, in duplicate, the words "Within city limits" and "Speed - limit 5 65 miles per hour," and the card 12 bears the words "Country speed - limit 10 miles per hour."

The cards bearing the designations as thus described are adapted to be utilized in the 70 following manner: A complete pack will consist of one hundred cards, fifteen each of cards 1 and 9, ten each of cards 2, 3, 4, 8, and 10, five each of cards 11 and 12, four each of cards 5 and 6, and two of card 7. 75

The design of the game is to have the contesting players run an automobile race of an even fifty or one hundred miles, and the mile-cards (shown in Fig. 1) are provided to indicate the number of miles a player progresses 80 at a particular play. At the close of the game if a player should play any mile-card except one which would make exactly fifty or one hundred miles he forfeits the score already made. 85

The three cards shown in Fig. 2 are designed to impede the progress of the players, and the number of hours named on said cards indicates the number of miles the player's score is to be set back. For instance, if the card says "Delay two hours" and the "country" card shown in Fig. 4 is governing the play at the time the opposite side to the one playing the delay-card would be required to deduct twenty miles from any 95 score previously made, because the permissible speed in the country is reckoned as ten miles per hour. If the card "In city limits" happens to be governing the play, the deduction would be five miles for each hour delayed, as five miles per hour is the limit of speed fixed by the game for city travel.

A "Within city limits" card is said to govern the game until one side or the other plays the card "In country." This card 105 having no speed-limit that can be exceeded

by any of the "mile" cards, permits any mile-card being played until some player retards rapid progress by again playing a "Within city limits" card. Thus the two 5 cards 11 and 12 govern the play as indicated. The delay-cards are designed to obstruct or suspend the play, and an aim of the player should be to interrupt his adversary's play by the use of these delay-cards.

10 The three cards shown in Fig. 3 may be termed "permission-cards," each bearing a relation to the delay-cards. If a player is delayed, for example, by his adversary playing the delay-card 6, ("Out of gasolene,") he 15 could resume play by the playing of the card 10 ("Gasolene") and afterward the card 10 ("Go.") If the playing of the delay-card 5 ("Collision") obstructs a player, he can resume play by the playing of the card "Hauled 20 in" and afterward the "Go" card, and if the delay-card "Puncture" is played against a player he is relieved by the play of the "Go—The start" card.

25 The foregoing brief explanation will suffice to give a general idea of how the cards may be utilized in playing a game.

The detail rules of the game need not be given, as they may be optional as to many details and do not constitute a part of the 30 invention as hereinafter claimed.

What I claim, and desire to secure by Letters Patent, is—

1. A game comprising a series of cards having numerical designations thereon indicating distance, a second series of cards bearing designations indicating that the score of 35

one or more players is to be suspended, a third series of cards containing designations permitting the score to be counted, and a fourth series of cards containing characters 40 or designations regulating the rate of scoring.

2. A game comprising a series of cards bearing numerical designations indicating a distance traveled, a second series of cards bearing varying designations each indicating 45 that the score of a player is to be suspended and for what cause, a third series of cards bearing designations indicating the right of a player to proceed to score, and a fourth series of cards containing designations which govern 50 the rate at which the score is to be counted.

3. A game comprising a series of cards each bearing a number indicating a distance traveled by an automobile, a second series of 55 cards bearing designations indicating that the progress of the player is to be delayed as "Out of gasolene," "Collision" or "Puncture;" a third series of cards bearing designations which indicate that a player has permission to score, as "Gasolene" "Hauled in" and "Go," and a fourth series of cards bearing designations prescribing the rate at which the score may be counted, as "City 60 limits" and "Country."

65 In testimony whereof I affix my signature in the presence of two witnesses.

WILLIAM JANSON ROCHE.
